UNITED STATES PATENT OFFICE

EDWARD H. LOFTIN, OF NEW YORK, N. Y., ASSIGNOR TO GENERAL RAILWAY SIGNAL COMPANY, OF ROCHESTER, NEW YORK

METHOD OF AND APPARATUS FOR ELECTRICAL SIGNALING

Application filed October 4, 1934. Serial No. 741,702.

While my invention relates generally to systems of electrical signaling, it has for a particular object the provision of a system of railway signaling.

A particular object is to provide a system that is simple and effective, and yet one that will furnish the locomotive operator with a large amount of information as to track conditions.

Another object is to use the rails or trackways as electrical circuits to carry the signal currents, and to use the same signal currents to cause the operation of the wayside visual signals as well as the visual signals and automatic controls on the locomotive.

A further object is to superimpose upon the track currents definite code or signal combinations indicative of track conditions, to be able to vary the combinations in accordance with changing track conditions, and to selectively interpret the signal combinations on the locomotive into visual or other signals in keeping with the track conditions.

A still further object is to prevent the changing of the signaling currents in accordance with signal combinations from interfering with the wayside signal governing devices where the change does not demand a new setting of the wayside visual signals.

An important object is to provide for current failures through the system's indicating a "danger" condition in the part of the system affected by the current failure.

The system also provides means for definitely indicating open draw bridges, open switches, workmen engaged in track work not permitting traffic, and the like, as well as means permitting the locomotive leaving signaled territory and reentering signaled territory, and being definitely informed of these facts.

Other objects and advantages will be obvious to those skilled in the art following a description of the system and discussion of its mode of operation.

In carrying out my invention I employ as a means of communication between the trackway and vehicle a form of Baudot code signal. This form of signal is of particular advantage in that it permits of a large num-

ber of codes or signal combinations, each one of which may be employed to selectively choose one of a large number of controlling operations at the receiving station and set it into action.

My invention will be best understood by reference to the accompanying drawings in which

Fig. 1 diagrammatically illustrates a complete system;

Fig. 2 diagrammatically illustrates a provision that may be made at the exit end of signaling territory to inform the locomotive of the fact that signaling territory is being left;

Fig. 3 diagrammatically illustrates a provision that may be made at the entrance end of signaling territory to inform the locomotive that signaling territory is being entered, and

Figs. 4 and 4a are diagrams explanatory of the code signal formation.

Referring to Fig. 1 the reference numerals 1, 1 designate the track rails of a railway over which traffic normally moves in the direction indicated by the arrows; that is, from left to right. The rails are divided, by means of insulating joints 2, into a plurality of successive track sections or blocks A—B, B—C, C—D, etc. The track in block C—D is shown as broken but it will be understood that in practice the track will be continuous. Each track section or block is provided with a track circuit comprising the track rails themselves, a circuit including a transformer T at the exit end of the block for supplying alternating current to the rails, and a circuit including one winding of a relay H at the entrance end of the block.

Each relay H, in the form shown, is of the polyphase motor type, comprising two stator windings 3 and 4, and a rotor 5 which actuates the contact finger 6. The winding 3, which I will term the track winding, is connected directly with the track rails of the corresponding block, while the other winding 4, which I will term the polarizing winding, is permanently supplied with alternating current from the same source as the track rails, via the supply mains 7 and generator

7a. With such a relay when current is sent through the track winding 3 in one phase the rotor 5 is actuated in one sense, when current is sent through the winding in an opposed phase the rotor 5 is actuated in the opposite sense, and when there is no current in the track winding, or none in the polarizing winding, or none in both windings, the relay is deenergized and the rotor takes up a neutral position. The relay therefore provides for three positions based on shifting phase of current in the track circuit and stopping current flow.

The contact finger 6 is arranged to control three circuits through making (position) contact with contactors 8, 9 and 10. Each one of these circuits includes one of the signal lamps G, Y, R, the three lamps comprising the usual wayside visual signaling system in which the lamp G has a green lens to indicate "clear", the lamp Y a yellow lens to indicate "caution", and the lamp R a red lens to indicate "danger". The same currents that operate these lamps may be employed to set other visual signals, such as semaphore arms, if desired. The lamp circuits are shown as deriving their currents from the mains 7, though any other suitable current source may be employed.

30 The current passing through lamp R energizes relay 11, and current through either lamp Y or G energizes the relay 12, resulting in control of the lever 13 to throw either of the two signal producing wheels 15 or 16 under the brush 17, the two wheels being rotatably fixed but slidably mounted on the shaft of the motor 18, or the lever may as well move the brush 17 in lieu of the wheels. The position of the lever 13 also determines the phase of the current supplied to the transformer T through operation of the pole-changing switch 19. Resistance 20, in circuit with the feeder to transformer T prevents excessive current being drawn in case of short circuit of the track circuit as happens when the block is occupied by one or more cars.

50 The signal producing wheels 15 and 16, being one at a time in circuit with the feeder to the track circuit superimpose upon the track currents interruptions which may be so chosen in time and number as to make definite signal or code combinations in a manner which will be described later. Wheels 55 arranged for definite code combinations distinctive of the particular track conditions at different points may be inserted as desired. For instance, there may be chosen ten code combinations all of which have as a first meaning, "track clear", but the first one of which adds, "sharp curve, slow down"; the second adds, "up-grade open throttle"; the third adds, "draw bridge—slow speed"; and so on. The code combinations are for use 60 on the locomotive, and the manner of get-

ting them there and making use of them will be described later.

The description so far outlines the general system for exciting the track circuits, and before proceeding with special features 70 and the communication of the signals to the locomotive, the operation of the system so far outlined will be recited:

Beginning with block C—D, if there is a car in the block, a broken rail, or other conditions such as the closure of short-circuiting switch 21 (the purpose of which will be described later), which prevents track current from exciting the winding 3 of relay H at point C, the relay H is deenergized and 75 contact finger 6 takes up a neutral position making contact with contactor 10. This closes the circuit through lamp R which is indicated as lighted, thus setting the wayside visual signal at C to a "danger" or 80 "stop" indication. Current also flows through relay 11 which, acting through lever 13, sets brush 17 on signaling producing wheel 15 and pole changing switch 19 to the right. This setting permits the excitation of 85 track circuit B—C with current of one phase having superimposed upon it interruptions of a definite code combination determined by the structure of wheel 15. The track current passes through winding 3 of relay H 90 at point B, and its phase is such as to actuate the rotor 5 in a clockwise direction to make contact between contact finger 6 and contactor 8. As before stated, there are interruptions in the current due to signal wheel 100 15 so that the relay H is preferably constructed sufficiently slow acting or damped to prevent response or chattering due to these interruptions. I will explain later how the interruptions are made of very short 105 duration and form only a small part of the time of one revolution of the signal producing wheel, thus making the matter of preventing response of the relays H very simple. Current passes through the contactor 8 to lamp Y, indicated as lighted, thus 110 setting the wayside visual signal at B to a "caution" indication. Likewise, the code combination superimposed by wheel 15 on the current in block B—C is one chosen to 115 interpret "caution". Current also flows through relay 12 at B, thus setting the lever 13 the reverse of the setting at point C, which sets brush 17 on signal producing wheel 16 and pole-changing switch 19 to the left. The 120 track circuit of block A—B is therefore excited with current opposite in phase to the current in block B—C and the current has superimposed upon it code combinations due to wheel 16 which are different from wheel 15. As a result rotor 5 of relay H at point 125 A is actuated in an anti-clockwise sense to make contact between contact finger 6 and contactor 9, thus sending current through lamp G, indicated as lighted, setting the 130

wayside visual signal at A to a "clear" or "proceed" indication. Likewise, the code combination superimposed by wheel 16 on the current in block A—B is one chosen to interpret "clear". Since additional indications to the rear, or beyond point A, will also be "clear" indications, the same setting of the pole-changing switch 19 and the signal producing wheels 15 and 16 at the point A as at the point B will suffice, so that one relay 12 through which currents of both lamps Y and G pass suffices for setting the pole-changing switch and wheels. As before stated, the wheels 15 and 16 at the different points may have different code combinations, but in general the combinations on wheel 15 should come under the general head of "caution" and combinations on wheel 16 under the general head of "clear".

The system is particularly adapted to making special signals to indicate special roadway conditions, one of which I have illustrated in the block C—D, in which 22 represents a drawbridge. The drawbridge is arranged to close-circuit the circuit containing battery 25 and relay 26 when closed for train traffic, and to open circuit the system when opened for water traffic. When the drawbridge is open the normal block track current is interrupted so that without any special provisions, the signals at point C would be set at "danger" indication, but the usual interpretation given to a danger indication is to stop and then proceed slowly, leaving it to the engine operator to ascertain the cause of the "danger" indication. With my system a signal can be transmitted to the locomotive engineer before he arrives at the drawbridge telling him to "stop and stay", which signal will continue as long as the drawbridge is open, as follows: Current is supplied to the track circuit at the entrance side of the drawbridge through a special transformer ST when opening of the drawbridge causes relay 26 to release the switch 27 to close the connection of transformer ST to the track circuit. Some distance in advance of the drawbridge, as at point X, the track circuit is connected to a short circuiting switch 21 which operates in unison with switch 27. A code signal producing wheel 28, on the shaft of the motor 18, superimposes a special code signal combination on the current in the track between the point X and the drawbridge. The switch 21 short circuits the special signal current from the track winding 3 of the relay H at the point C. A track switch into a siding or spur could be made to operate this special signal connection in the same way as the drawbridge illustrated, thus giving protection against a switch opening.

The operation is as follows: with the drawbridge 22 closed the block track circuit is normal and the relay H is excited by the

normal track currents. When the drawbridge is open the normal track currents are interrupted and a special signal current is impressed on the track between the point X and the drawbridge. The track circuit between the points C and X is without current due to short circuit by switch 21. The signals at C are therefore set at "danger". A locomotive arriving at C notes a normal "danger" signal and proceeds into the section C—X where the absence of current causes an application of brakes to stop the locomotive which stop is not permanent, but permits proceeding at low speed after stopping. Upon proceeding beyond point X the locomotive receives the special signal to "stop and stay" which remains impressed as long as the drawbridge is open.

It may be desirable to include in a railway signalling system facilities which will permit an authorized work foreman to set a signal against proceeding into a section where work is going on which work will not permit traffic. This may be made possible by providing special signal arrangements, as that indicated for the drawbridge, from point to point along the trackway, which signals can be thrown into operation by a key in possession of the foreman, as I have shown in connection with the special signal, where 29 is a key lock having a bolt 30 to operate the switch 21, as well as switch 27, through the connection between the two switches indicated by the broken line.

The foregoing provides for exciting the track circuits of the various blocks with alternating currents which set the wayside signals in accordance with phase of currents and/or absence of currents depending upon track conditions, and for impressing upon the track currents interruptions in the form of code signal combinations determined by the setting of wayside signals, or special signal arrangements set in the system. I will now describe the manner in which use is made of these code signals on the locomotive, pointing out first that the locomotive receiving apparatus takes no account of the phase changes employed to determine two of the positions of the wayside signal relays, but is concerned with the code signals or interruptions in the current and the total absence of current.

In Fig. 1 all of that part of the diagram above the track rails 1, 1 is illustrative of the apparatus carried by the locomotive. A pick-up coil 31 is attached to the locomotive preferably just forward of the forward truck 32 so as to be quite close to the track circuits. The pick-up coil circuit may be electrically tuned to the frequency of the signaling alternating currents in the track circuits, as by a condenser 33, to minimize possibility of interference from stray currents. The received currents are suitably amplified by an ampli-

fier 34, which may be of the well known three-electrode vacuum tube type in one or more stages, the circuits of the various stages being electrically tuned if desirable, to actuate the main receiver relay 35 controlling the switch 36. It should be noted that the switch 36 is held open when current flows in the track circuits, and closes during the interruptions that make the code signals and on a total failure of current. A rotative element 37, having cam 37a, starts with spring contact 38 closed, and closes spring contacts 39, 40, 41 and 42 in succession. The element 37 is rotated by motor 43 through a friction wheel 44, rotatably fixed and slidably mounted on the shaft of the motor, capable of making friction driving contact with friction wheel 45 fixed to the rotative element. The rotative element is started and stopped by a pawl lever 46 cooperating with a notch in a rim 47 fixed to the element. A clutch arm 48 on the pawl lever 46 cooperates with the friction wheel 44 to bring about contact with the friction wheel 45 at the starting moment. With the rotative element at rest, as illustrated, contact 38 is closed, so that closure of switch 36 will send current from battery 50 through relay 49 to actuate pawl lever 46 to start the rotative element. Contact 38 immediately opens to deenergize the relay 49, leaving the pawl lever 46 riding on the surface of the rim 47 ready to stop the rotative element when one revolution is completed.

Referring temporarily to Fig. 4, which represents one of the signal producing wheels at the wayside stations, it will be seen that I have divided the circumference of the wheel into a one-third sector, having spaced insulating segments *a*, *b*, *c*, *d*, and a two-thirds sector, having no segments, which sectors may be termed "signaling" and "non-signaling" respectively. Fig. 4a illustrates the current that will flow in a track circuit during one revolution of such a wheel, showing that the duration of current flow is long compared to the absence of current, which fact makes the design of a wayside relay *H* that will not respond to the code signaling a simple matter.

The description so far will permit of following the first step in the operation of the receiver on the locomotive. Referring to Figs. 4 and 1, when the brush 17 comes to the insulating segment *a* on the signal producing wheel an interruption in current takes place, causing the relay 35 to release the switch 36 to close the main receiving circuit. The rotative element 37 is at rest with contact 38 closed, which permits current to flow from battery 50 through contact 38 and switch 36 to energize relay 49, operating the pawl lever 46 to start the rotative element on a revolution. The brush 17 passes off insulating segment *a*, permitting current to flow resulting in opening of switch 36. The movement of

the rotative element opens contact 38 to remain open until the end of the revolution, thus deenergizing relay 49 and leaving pawl lever 46 free to stop the rotative element. Brush 17 arrives at insulating segment *b*, again closing switch 36. At the same time cam 37a of the rotative element closes contact 39, allowing current to flow from battery 50 in a circuit including switch 36 and contact 39. The same procedure results as brush 17 passes insulating segments *c* and *d* and cam 37a passes contacts 40 and 41 respectively. When cam 37a arrives at contact 38, brush 17 is on the "non-signaling" sector of the wheel and switch 36 is held open, so that contact 38 may be closed without energizing starting relay 49, but paves the way for repeating the cycle as soon as the brush again arrives at the "signaling" sector.

It is apparent that the relative angular velocities of the signaling wheel and the rotative element should be adjusted so that the rotative element completes one revolution in the same period of time, within limits, required for the signaling wheel to revolve through the signaling sector, and that the relative spacing of the insulating segments on the signaling wheel and the contacts in the path of the rotative element cam should be such that corresponding units are reached at the same time, within limits; that is, synchronized ready for action. In practice, the signaling wheel and the rotative element cam are synchronized at every revolution of the former, the cam being held stationary by the lever 46 while the signaling wheel turns through that portion of its cycle during which the brush 17 is in contact with the non-signaling sector, and the cam being started just as the signaling wheel turns its signaling sector *a* into contact with the brush 17. The duration of the signal interruptions at the signaling wheel or transmitter and the contact closures at the rotative element cam or receiver can be made sufficiently long to be certain of an overlap even with relative angular velocities differing as much as 10% from exact synchronism. In practice there is no difficulty in preserving motor speeds within 1 or 2% with ordinary commercial apparatus, and much better if precision warrants special apparatus. Since all of the transmission motors may be connected to the same alternating current transmission line, as illustrated in Fig. 1, the same speed of all would be assured in the use of induction motors, which fact greatly simplifies the matter of adjustment of motor speed on the locomotive.

While I have divided the signaling wheel into one-third signaling and two-thirds non-signaling sectors, no such definite relation is required. It is desirable however to have a non-signaling sector of greater duration than the signaling sector because it may often

happen that conditions in the track may operate to cause the signaling wheel 16 to be moved out of contact with the brush 17, and the wheel 15 to be moved into contact there-
 5 with, which might cause the rotative cam 37 on the locomotive to start in response to an impulse derived from one of the intermediate insulating segments, such as *b*, *c*, or *d* on the wheel 15 and thus would operate the cam
 10 37 out of step, so to speak, with the wheel 15, giving a false signal. In the arrangement shown, the non-signaling sector on each signaling wheel permits the cam 37 to return to its original or initial position after each
 15 false start, so that the cam and the signaling wheel are never out of step to give a false signal for more than one revolution of the wheel. The false signal itself will not register, as will be later explained, and will do
 20 no harm as long as the rotative element comes to rest in time for the correct starting signaling. The relatively wide non-signaling sector adequately provides for this.

Continuing with the description of the apparatus and operation of the locomotive installation, the contacts 39 and 40 control circuits through relays 51 and 52 which relays in turn determine the settings of multiple selector contacts 53 and 54 respectively. The
 25 multiple selector 53 is provided with three movable contacts 80, 81 and 55, and the selector 54 is provided with two movable contacts 82 and 56. The contacts, relays and multiple contacts may be termed the selector elements
 30 of the receiver. Now it is apparent that with two multiple contact elements, each capable of two positions, we can selectively choose any one of four circuits for closure; as I have illustrated, there are four combinations of
 35 positions which these multiple contacts may occupy, as follows: Both to the right; both to the left; upper one to right, lower one to left; and upper one to left, lower one to right.

Referring again to Fig. 4, the two positions
 40 occupied by the insulating segments *b* and *c* may be termed the selector positions, since they are the ones under the brush 17 when the selector contacts 39 and 40 are closed. The code signals are therefore made by in-
 45 serting or leaving out insulating segments at these positions.

Now suppose when position *b* is reached there is no insulating segment, then in spite of the fact that contact 39 is closed switch
 50 36 remains open due to continuation of current during this interval, and relay 51 is not energized because contact 39 and switch 36 are in series with battery 50 and relay 51. Multiple contact 53 therefore remains to the
 55 right. On the other hand, if there is an insulating segment switch 36 closes, resulting in the multiple contact being pulled to the left. The same thing happens when selector position *c* is reached in regard to contact 40, relay 52 and multiple contact 54.

The multiple contacts 53 and 54 temporarily remain in the left hand positions, if so selected by the code signals, after the opening of contacts 39 and 40 respectively, through the operation of stick circuits, closed
 60 through contact 55 for multiple contact 53 and through contact 56 for multiple contact 54. The stick circuit for the relay 51 may be traced as follows:—From the battery 50 direct to the lower terminal of the relay 51,
 65 from the upper terminal of the relay 51 to the contact element 55 which is in its left-hand position, thence to the switch 57 and direct to the battery 50. The stick circuit for the relay 52 may be similarly traced as fol-
 70 lows:—From the battery 50 to the lower terminal of the relay 52, from the upper terminal of the relay 52 to the contact 56 in its left-hand position, thence through the switch 57 to the battery 50. These stick cir-
 75 cuits are controlled by relay 58 through switch 57. When the rotative element 37
 80 nears the end of a revolution the cam 37a closes contact 42, which is in circuit with relay 58 and battery 50 independent of switch 90
 85 36, thus energizing relay 58 to open switch 57, clearing out the stick circuits and returning the multiple contact elements 53 and 54 to normal position ready for a new signal. The energizing circuit for the relay 58 includes
 90 the relay 49 which is therefore temporarily energized when the relay 58 is energized, but this energization of the relay 49 has no effect on the operation of the apparatus as the cam portion 37a immediately disengages the contact 42 and de-energizes the relay 49, permitting the lever 46 to drop into the depression in the collar 47 and thus stop the rotative element as described above. The signal cir-
 95 100 cuits will be traced hereinafter.

Before the clearing out operation takes place there is a signal of execution brought about by insulating segment *d* on the wheel, which comes under the brush at the same time that contact 41, controlling relay 59, is closed. 110 During the selection operations switch 60, operated by relay 59, remains open so that as each selector position is taken up there is no false selection of a control circuit. When the selector multiple contacts are finally set 115 to choose the desired control circuit switch 60 is closed by a signal originating with segment *d* on the signaling wheel, and the selected control circuit thus energized by battery 50. Now this execution signal could be 120 made locally as just previously described for the clear-cut signal, but there is a decided advantage in having it originate with the transmitter. In case a false signal starts the rotative element it would, in its passage 125 through the various contacts, make some sort of false selection of multiple contact positions, and if the signal of execution is accomplished locally, the false signal would be registered. But by requiring the signal of 130

execution to originate at the transmitter after a definite true signal, there is little likelihood of a false signal ever being accompanied by a correctly timed signal of execution, and therefore registry of a false signal is not likely. This arrangement well provides for not registering false signals due to shifting of signaling wheels, as previously described. However, even though a false signal should 10 register, no harm would be done, as the true signals are rapidly repeated, two or three times a second being possible, so that any false signal would be corrected before it would have time to put any of the mechanical train control apparatus into operation, which is an extremely valuable feature of my system.

The system, as so far described, provides for selecting any one of a plurality of control circuits on the locomotive in accordance 20 with any one of a plurality of code signal combinations, informative of track conditions, of a permanent, semi-permanent or temporary character, superimposed upon a track alternating current variable in characteristics in a manner suitable to operate wayside signal relays without interfering with the locomotive code signal combinations. The selectable control circuits may be 25 made to control any desired functions on the locomotive, one at a time or in combination, such as lighting visual indicating colored lamps, operating warning bells or whistles, controlling air brake mechanisms, setting 30 cams, which determine the run down distance under application of brakes and speed limits imposed, and the like. The particular manner of putting the control circuits to work does not form a part of my invention. 35 In Fig. 1, however, I have shown an illustrative use of the control circuits in connection with colored light visual indicators, it of course being understood that an electric current which is available to light a lamp may 40 be made to do anything else desired, either directly or through well known intermediary apparatus. The four circuits, as and when selected, energize relays 61, 62, 63 and 45 64 through battery 50. When the relay selected is energized to close one of the contacts 65, 66, 67 and 68 respectively, current flows from the battery 69 through one of the lamps R, Y, G and G respectively as well as the winding of the corresponding relay to keep the light circuit permanently closed, as the energizing by the battery 50 is only temporary during the signal of execution. For instance, I have shown the second G lamp lighted through closure of contact 68. To keep this lamp from remaining lighted in case a signal for another one is made I provide the conducting wheel 70 in circuit with the battery 69 and the lamps through brush 72, the wheel having an insulating segment 71. The wheel rotates in synchro-

nism with the rotative element 47, indicated by the broken line connection between the two as by being on the same shaft, and the insulating segment is so located as to come under the brush during the signal of execution, but not to break the circuit during the entire period of the signal of execution. In this way an old signal indication will give way to a new one or, if the same old signal is made, no interruption of the indication will take place. I have shown two G lamps as indicative of the fact that there may be a plurality of signals under the general head of "clear" if track grades, curves and the like warrant imposing different speeds under clear track conditions.

In order to illustrate the manner in which the various locomotive or cab signals shown may be displayed by different code signals from the various wayside signal wheels, I will now trace the locomotive signal pick-up circuits. If one of the signaling wheels, say the wheel 16, is connected to the track rails of the block in which the vehicle under consideration is travelling, and this wheel is provided with the insulating sectors *a*, *c* and *d* only, the sector *b* being a conducting portion, the relay 51 remains de-energized while the relay 52 is energized at the rotation of the element 37. The multiple contact selector 53 therefore remains in the right-hand position while the selector 54 is moved to the left-hand position, and when the relay 59 is energized by the signal of execution, closing the switch 60, the following pick-up circuit for the relay 61 is completed:—From the battery 50, through the switch 60 to the contact 82, thence through the left-hand stationary contact to the movable contact 81, and to the lower terminal of the relay 61, from the upper terminal of the relay 61 to the battery 50. The energization of the relay 61 closes its front contact, thus completing a stick circuit for this relay through the left-hand signal lamp G, this circuit being traceable as follows:—From the battery 69 to the upper terminal of the relay 61, from the lower terminal of 61 through its front contact 65 and contact finger, through the lamp G, the brush 72 and the wheel 70 to the battery 69.

In a similar manner, if both of the insulating sectors *b* and *c* are omitted from a wayside signaling wheel which may be the signaling wheel 15, both of the multiple contact selectors 53 and 54 remain in their right-hand positions as shown, and upon the signal of execution closing the switch 60, a pick-up circuit for the relay 62 is completed, which circuit may be traced as follows:—From the battery 50, switch 60, movable contact 82 of the selector 54, movable contact 80 of the selector 53, relay 62 and back to the battery 50, the energization of the relay 62 closing a stick circuit through its front contact 66 and the signal lamp Y indicating the battery 69, the

wheel 70 and the brush 72, which circuit is obvious from the drawings.

With the insulating sector *c* omitted from the wayside signaling wheel, which may be the special wheel 28, the selector 53 is placed in the left-hand position while the selector 54 remains to the right, and when the switch 60 is closed by the signal of execution, a pick-up circuit for the relay 63 is closed from the battery 50 through the switch 60, the movable contact 83 of selector 54 and the movable contact 80 of selector 53, the relay 63 and return to the battery 50. The energization of the relay 63 closes its front contact 67 and completes a stick circuit for this relay from the battery 69, this circuit including the special signal lamp G and being traceable in a similar manner to the stick circuits for the lamp Y and the left-hand lamp G.

If a special wayside signal wheel 28 has both of the insulating sectors *b* and *c*, or if for any reason no signaling current flows in the track coils or is received by the locomotive coil 31, both of the relays 51 and 52 are energized in the rotation of the element 37 and both of the selectors 53 and 54 are moved to the left, completing a pick-up circuit, when the switch 60 is closed by the signal of execution, which pick-up circuit energizes the relay 64. This circuit may be traced as follows:—From the battery 50, switch 60, movable contacts 82 and 81, the relay 64 and the return wire to the battery 50. The energization of the relay 64 completes a stick circuit through its front contact 68 and the right-hand danger signal lamp R, this circuit including the battery 69, the wheel 70 and the brush 72 as clearly traceable in the drawings.

The various signals thus energized in response to different codes or successions of time-spaced interruptions in the trackway current may be utilized to communicate certain trackway or traffic conditions to the engineer. Thus the left-hand signal lamp G may indicate "clear no speed limitations", the signal lamp Y may indicate "caution that usually precedes a danger signal", other signal lamp G "clear with track structural conditions in block which require caution", and the right-hand signal lamp R "stop and stay". Any other suitable combination of signals or other indicators may be used in place of the specific arrangement shown, or the stick circuits of the relays 61, 62, 63 and 64 may be utilized to operate suitable brake control apparatus to control the train speed in accordance with the traffic or trackway conditions encountered.

An important feature of my invention is that it meets, in a very simple way, the broad fundamental requirement that a failure of current will register as a danger signal both at the wayside stations and on the locomotive. I have already shown how absence of

current in the track circuit blocks, through any cause whatever, will set the wayside visual signals at "danger" indication through the operation of the polyphase motor relays H. It will be noted that instead of the usual procedure of operating a receiving relay during current flow I employ a no current period or interruption. Therefore when there is no current in the block entered by the locomotive the relay 35 is continuously deenergized, leaving the switch 36 always closed, with the result that the rotative element continues to rotate, each time setting all the relays just as if a signal wheel having all the selector positions insulated as illustrated in Fig. 4 were rotating, and making a signal of execution and clear-out signal. By adopting the control circuit selected by having all of multiple contact selectors to the left as the "danger" control circuit, danger is indicated on the locomotive by current failure. Should current fail in the transmission line 7 or in the feeders to the transformer T, the track circuits of the blocks fed will be without current and indicate the fact at the wayside signal and on the locomotive, as before described. If current fails in the signal light feeder the relays 11 and 12 will not be capable of being energized, so that the lever 13 will take up a mid-position, entirely opening the pole changing switch 19 and cutting off current from the corresponding block.

While I have illustrated my system as capable of making four selections, I have done so merely for simplicity, as any number of selections is possible within reasonable practical circuits. In referring to Fig. 4, I stated that positions *b* and *c* on the wheel are the selector positions. Now if we increase the number of such positions to three, increasing the corresponding selector elements at the receiver, eight combinations will be possible. Four selector positions and corresponding receiver selector elements makes sixteen selections possible, and five sets of positions and elements makes thirty-two selections possible. Extremely simple and practical apparatus capable of thirty-two selections is a proven success.

While I have illustrated the selector as an arrangement of electrical contacts and relays, I have done this merely for the sake of simplicity of explanation of the system. The same result can be accomplished through a system of mechanical selectors cooperating with the relay 35 and the rotative element 47. I do not, however, make any claim to the selector system per se.

The system is particularly adapted to railways having only portions of their systems equipped for signaling. Under such conditions it is desirable to inform the locomotive when it leaves signaled territory and to set the locomotive apparatus against making false danger signals when it arrives on tracks

not having signaling currents, as well as to inform the locomotive when it is about to enter signaled territory and to set the apparatus for receiving signaled territory signals.

5 In Fig. 2 I illustrate a portion of the trackway of the last block of signaled territory and a portion of the trackway of the non-signaled territory comprising rails 1, 1 and insulated joints 2, 2. The signaled block 10 is excited with current from a transformer T as previously described. A short section of the non-signaled territory just beyond the last block is excited with a signaling current through a transformer NT, a special signaling wheel 28 on the shaft of the motor 18 superimposing upon the current a code combination meaning "leaving signaled territory". The special signaling wheel 28 is connected to the transformer NT through a circuit including the generator 7^a, the lower wire of the transmission line 7, through a resistance unit 20 and a brush to the shaft of the rotor 18, from the wheel 28 through the brush bearing thereon to the primary 25 of the transformer NT, and thence through the upper wire of the transmission line 7 to the generator 7^a. The special track circuit is completed through an ordinary two-position relay H, as there are only two 30 track conditions to indicate, one being when the special track circuit is not occupied, indicating a clear condition, and the other when the track circuit is occupied, indicating a danger condition, as illustrated in Fig. 2 35 by the truck 32 of a locomotive in the section. The relay H makes contact at 9 or 10 accordingly as the special section is or is not occupied to show lights G or R and also to excite relays 12 or 11, operating lever 13 to set 40 wheels 15 or 16 and pole changing switch 19 as previously described.

The special signal is collected on the locomotive and selected as in the case of Fig. 1, and I have not again illustrated 45 the selector system in detail. It should be understood that the pick-up circuits for the relay connected to the selector in Fig. 2, including the relay 73, are selectively closed in response to distinctive code signals from various wayside signaling wheels, and that the particular code signal impressed 50 on the track rails of the first short section of non-signaled territory through the transformer NT operates the selector to close a pick-up circuit for the relay 73. The energization of the relay 73 closes its front contact and completes a stick circuit including 55 the signal lamp NS, one winding of the relay 74, which circuit may be traced as follows:— From the battery 69, upper terminal of the 60 relay 73, lower terminal of this relay through its front contact and contact finger, lamp NS, one winding of the relay 74, brush and wheel 70 to the battery 69. The relay 74 is preferably constructed with two separate wind- 65

ings, these windings being arranged so that the energization of the winding connected in the stick circuit just traced attracts the relay armature and opens the switch 75, while the other winding acts to oppose this winding. The purpose of this arrangement will be hereinafter explained. The energization of the lamp NS indicates to the engineer that he has entered non-signaled territory and is no longer proceeding under the protection of automatic control. The energization of the relay 74 through the stick circuit traced closes the switch 76 and opens the switch 75. The closure of the switch 76 shunts out the wheel 70 and its brush through an obvious circuit thus preventing the insulating segment in the wheel 70 from opening the stick circuit to the relay 73. The opening of the switch 75 prevents the energization of the danger signal lamp R as the train proceeds in non-signaled territory. As the train proceeds out of the block energized by the transformer NT, no code signal is transmitted to the selector, and hence the selector circuits act to close a pick-up circuit for the relay associated with the lamp R as described in connection with Fig. 1. This relay is therefore energized, but the lamp R is not lighted as no stick circuit for this relay is completed due to the fact that the switch 75 in this stick circuit is opened as explained above, and is maintained opened as the train proceeds through the non-signaled territory by the relay 74.

Fig. 3 illustrates an arrangement for informing the locomotive of arrival at signaled territory and setting the apparatus for normal signaling reception. The track rails 1, 1 are divided into track circuits by insulated joints 2, 2, the section from A' to A being the first block containing locomotive 105 signaling current, and the point A being the first point having wayside signals. The section A'—A is excited with signaling currents in a manner fully described heretofore. Immediately in advance of the point A' the rails have impressed upon them signaling current through the transformer ST, and a special signal superimposed on the current by the signal producing wheel 28 on the shaft of the motor 18. Special insulated joints 2' may be inserted in the rails to limit the distance to which the special signaling current will be effective. No current will flow until the truck 32 of the locomotive passes beyond the joints 2' to complete the 110 circuit.

The code signal supplied to the track rails of the last short block in non-signaled territory through the transformer ST from the wheel 28 is arranged to cause the selector on the locomotive to close a pick-up circuit for the relay 77 in a manner similar to the energization of the relays 61, 62, 63 and 64 described in connection with Fig. 1. The energization of the relay 77 closes its front con- 115 120 125 130

tact and completes a stick circuit through the lamp S, which circuit will be traced as follows:—From the battery 69, through the relay 77, and the front contact and contact finger thereof, the signal lamp S, the opposing winding of the relay 74, the brush and wheel 70 to the battery 69. Since at the time that this stick circuit through the opposing winding of the relay 74 is closed, current is already flowing through the normal attracting winding of this relay and the stick circuit including the relay 73 and the lamp NS which circuit has been traced above, relay 74 no longer holds the switch 75 open and the switch 75 is moved by the spring to its closed or left-hand position, thus opening switch 76 connected thereto. The energization of the light S informs the engineer that he has entered signaled territory and is again under the protection of automatic control. The closure of the switch 75 completes the stick circuit for the danger lamp R so that this lamp may be energized in response to danger code signals which may be transmitted from the trackway as the train proceeds in signaled territory. The opening of the switch 76 removes the shunt from the wheel 70 and its brush, thus permitting this wheel to periodically break the stick circuits for all the signal relays as described in connection with Fig. 1. While the train is in the block energized by the transformer ST, relay 77 will be repeatedly energized and the lamp S lighted. Current will flow through the winding of the relay 74 in series with the lamp S after the circuit through the other winding of the relay 74 has been broken but this current does not cause an attraction of the armature 75. Fig. 3 illustrates this condition of the circuits, in which the circuit through the lamp S is closed and that through the lamp NS is broken, switches 75 and 76 remaining in their left-hand positions. The signal S is displayed only while the train is in the track block energized by the transformer ST, and when the train enters the first block A'—A of a signaled territory the proper locomotive signal lamp is lighted in accordance with traffic conditions ahead in the manner described in connection with Fig. 1.

Having fully described my invention, I claim:

1. In a system of sectional electrical signaling, a method of signaling which consists of dividing the system into a plurality of electrically distinct sections, exciting each section with alternating current signaling current, superimposing code signal variations on said signaling current to make one group of signals, and varying the phase characteristics of said current without regard to said code signals to make another group of signals.

2. In a system of electrical signaling the

method of multiple signaling which consists of generating a single alternating current signaling current, varying the phase of said alternating current to create one group of signals, and superimposing time-spaced variations upon said current without regard to said phase variations to create another group of signals.

3. A method of electrical signaling which consists of continuously generating an alternating current signaling current, superimposing code signals on said alternating current to make one group of signals, and varying the phase characteristics of said currents without regard to said code signals to make another group of signals.

4. A method of electrical signaling which consists of continuously generating an alternating current signaling current, dividing a definite time period of said current into two portions, superimposing code signals on one of said portions to make one group of signals, and varying the phase characteristics of said currents to make another group of signals.

5. A system of electrical signaling including means for the continuous generation of alternating current signaling current, means for superimposing on said current time-spaced variations characteristic of predetermined code signals, and means for varying the phase characteristics of said alternating current without regard to said signal variations.

6. A system of electrical signaling including means for the continuous generation of alternating current signaling current, means for impressing code signal variations on said current, and means for varying the phase characteristics of said current without regard to said code signals.

7. A system of electrical signaling including a plurality of electrically distinct sections, means for exciting each section with alternating current signaling current, means for superimposing code signal variations on said current, and means for varying the phase characteristics of said current without regard to said code signal variations.

8. A system of electrical signaling including a plurality of electrically distinct sections, means for exciting each section with alternating current signaling current, means for superimposing code signals on said current, and means for varying the phase characteristics of said current without regard to said code signals.

9. A system of electrical signaling including a plurality of electrically distinct sections, a circuit for exciting each section with alternating current, means for changing the phase characteristics of said current, means for detecting said phase changes, a plurality of means for superimposing code signal variations on said current, and means whereby

said phase change detecting means determines the phase and code signal impressed upon an adjacent section.

10. A system of electrical signaling including a series of electrically distinct circuits, means for exciting each of said circuits with alternating current signal current, means for impressing any one of a plurality of code signals on said current, means for changing the phase of said current, and means interlinking said circuits whereby the phase of said current determines the phase and code signals impressed upon adjacent circuits.

11. A system of electrical signaling including a series of electrically distinct circuits, means for exciting each of said circuits with alternating current signal current, means for superimposing code signal variations on said current, means for changing the phase of said current, a receiver in each of said circuits responsive to phase changes and unresponsive to said code signal variations, and a receiver which may be associated with any one of said circuits responsive to said code signals and unresponsive to said phase changes.

12. A system of electrical signaling including a series of electrically distinct circuits, means in said system consuming electrical energy including means for exciting said circuits with alternating signaling current, a rotative means for superimposing code signal variations on said current, means for changing the phase of said current, means for detecting the phase of said current, visual indicating means, means for varying the code signals, and a common source of supply for all of said energy consuming means.

13. A system of electrical signaling including a series of electrically distinct circuits, means for energizing each of said circuits with alternating current and imposing distinctive signals controlled by signals in adjacent circuits on said alternating current, and independent means in one or more of said circuits for suppressing the normal signal in at least portions of said circuits and impressing thereon a special code signal.

14. A system of electrical signaling including a series of electrically distinct circuits, means for energizing each of said circuits with alternating current and imposing distinctive signals controlled by signals in adjacent circuits on said alternating current, independent means in one or more of said circuits for suppressing the normal signal in at least portions of said circuits and impressing thereon a special code signal, and means controlling the going in or out of operation of said independent means.

15. A system of electrical signaling including a series of electrically distinct circuits, means for energizing each of said circuits with distinctive signal impulses controlled by signals in adjacent circuits, independent means in one or more of said circuits for sup-

pressing the normal signal impulses in at least portions of said circuits and impressing thereon special signal impulses, and a locking means for the placing of said independent means in or out of operation.

16. A system of electrical railway signaling including a track circuit, means for continuously exciting said circuit with alternating current signaling current, means for superimposing code signal variations on said current, means for changing the phase of said current, a receiver in said circuit responsive to phase changes and unresponsive to said code signals, and a receiver associated with said circuit responsive to said code signals and unresponsive to said phase changes.

17. A system of electrical railway signaling including a track circuit, means for continuously exciting said circuit with alternating current signaling current, a code transmitter superimposing signals on said current, means for changing the phase of said current, a receiver in said circuit responsive to said phase changes and unresponsive to said code signals, and a code receiver associated with said circuit.

18. A system of electrical railway signaling including a track circuit, means for continuously exciting said circuit with alternating current signaling current, means for superimposing code signal variations on said current, means for changing the phase of said current, a receiver in said circuit responsive to said phase changes and a failure of current and unresponsive to said code signals, and a receiver associated with said circuit responsive to said code signals and a failure of current and unresponsive to said phase changes.

19. A system of electrical railway signaling including a plurality of electrically distinct blocks, means for continuously exciting each of said blocks with an alternating signaling current, means for superimposing code signals on said current, and means for varying the phase of said current.

20. A system of electrical railway signaling including a plurality of electrically distinct blocks, means for continuously exciting each of said blocks with an alternating signaling current, means for superimposing a plurality of code signal variations on said current, means for varying the phase of said current, means in each of said blocks for detecting phase variations, and means linking adjacent blocks whereby the phase variations in one block control the phase adjustment and code signal variations in an adjacent block.

21. A system of electrical railway signaling including a plurality of electrically distinct blocks, means for continuously exciting each of said blocks with an alternating signaling current, means for superimposing code signal variations on said current, means

for varying the phase of said currents, a receiver in each of said blocks responsive to phase variations and unresponsive to code signal variations, and a receiver which may be associated with any one of said blocks responsive to code signal variations and unresponsive to phase variations.

22. A system of electrical railway signaling including a plurality of electrically distinct blocks, means for continuously exciting each of said blocks with an alternating signaling current, means for superimposing code signal variations on said current, means for varying the phase of said current, a receiver in each of said blocks responsive to phase variations and failure of current and unresponsive to code signal variations, and a receiver which may be associated with any one of said blocks responsive to code signal variations and failure of current and unresponsive to phase variations.

23. A system of electrical railway signaling including a track circuit, means for exciting said circuit with alternating signal current, means for varying the phase of said signal current, wayside visual signals, means in said track circuit responsive to said phase variations and failure of current selecting the setting of said wayside signals, means for superimposing a plurality of code signal variations on said track current, and means operating in accordance with the setting of said wayside signals for selecting said code signals.

24. A system of electrical railway signaling including a series of electrically distinct blocks, means for energizing each of said blocks with distinctive signal impulses controlled by signals in adjacent blocks, independent means in one or more of said blocks for suppressing the normal signal impulses in at least portions of said blocks and impressing thereon special signal impulses, and a locking means for the placing of said independent means in or out of operation.

25. A system of electrical railway signaling including a series of electrically distinct blocks, means for energizing each of said blocks with distinctive signal impulses controlled by signals in adjacent blocks, all comprising signaled territory; an unsignaled track at the exit end of said signaled territory, a section of track circuit between said unsignaled track and the exit end of said signaled territory, and means for exciting said section with a distinctive code signal.

26. A system of electrical railway signaling including a series of electrically distinct blocks, means for energizing each of said blocks with distinctive signal impulses controlled by signals in adjacent blocks, all comprising signal territory; an unsignaled track at the entrance end of said signaled territory, a section of track circuit between said unsignaled track and the entrance end of said

signaled territory, and means for exciting said section with distinctive code signal impulses.

27. A system of electrical railway signaling including a track circuit, means for continuously exciting said circuit with signaling current, means for dividing said signaling current, means for dividing said signal portions, means for superimposing code signals on one of said portions, a railway vehicle, and a code receiver on said vehicle responsive during said signaled portion of the time periods.

28. A system of electrical railway signaling including a track circuit, a rotary transmitting device for impressing a plurality of time-spaced code signals on said circuit, a vehicle passing over said track, a plurality of control elements on said vehicle, and a rotary receiver periodically synchronized with said rotary transmitting device and adapted to selectively energize said control elements in accordance with any one of said signals.

29. A system of electrical railway signaling including a track circuit, means for impressing a plurality of code signals on said circuit, a vehicle passing over said track, a plurality of control elements on said vehicle, a code receiver associated with and momentarily selectively energizing said control elements in accordance with said signals, and means for locking said elements in operating position when so selected.

30. A system of electrical railway signaling including a track circuit, means for impressing a plurality of code signals on said circuit, a vehicle passing over said track, a plurality of control elements on said vehicle, a code receiver associated with and momentarily selectively energizing said control elements in accordance with said signals, means locking said elements in operating position when so selected, and means releasing a locked element when another element is selected.

31. A system of electrical railway signaling including a track circuit, means for continuously exciting sections of said track circuit with alternating current signaling current, means for impressing code signal variations on said current, transient means interrupting the flow of current in portions of said sections, a railway vehicle passing over said track, a code receiver on said vehicle, a magnet to operate said receiver adapted to actuate the same on a cessation of current, and a control circuit on said vehicle adapted to be continuously selected and energized by said code receiver when continuously actuated through a prolonged cessation of current.

32. A system of electrical railway signaling including a railway vehicle, a plurality of control elements on said vehicle, a code re-

- ceiver associated with and selectively energizing said elements and means for interlocking three of said control elements whereby the energizing of one of said interlocked elements will render the other inoperative until the energizing of the third element releases said interlocking.
33. In an automatic train control system, means for communicating influences corresponding to traffic conditions from the trackway to a moving vehicle comprising a continuously driven trackway device for recurrently impressing a pre-arranged series of time-spaced electrical impulses on the track rails, car-carried means for inductively receiving said impulses through an intervening air gap, and car-carried apparatus for responding to said impulses, said car-carried apparatus being continuously driven in synchronism with said trackway device while said impulses are being transmitted.
34. In an automatic train control system, means for communicating influences corresponding to traffic conditions from the trackway to a moving vehicle comprising trackway apparatus comprising means for applying an alternating current to the track rails through one of a plurality of continuously driven commutators, each of said commutators acting to interrupt said current at different pre-arranged series of time-spaced intervals, means for reversing the phase of said alternating current in accordance with traffic conditions, means for controlling the interruption of said current by different commutators in accordance with the phase of said alternating current, and car-carried means for inductively receiving said current and responding to said series of interruptions.
35. In an automatic train control system for railways having portions of their trackway equipped for automatic train control and portions not so equipped, means for communicating influences corresponding to trackway conditions ahead from the trackway to a moving vehicle comprising trackway apparatus for applying electrical energy to trackway conductors in said equipped portions and recurrently interrupting said energy at a pre-arranged succession of intervals in accordance with traffic conditions ahead, for the trackway apparatus at the entrance to and the exit from said unequipped portions and recurrently interrupting the energy applied to a section of said trackway conductors at different pre-arranged successions of intervals, car-carried apparatus comprising means for inductively receiving current from said trackway conductors and means responsive to said various successions of interruptions.
36. Railway traffic controlling apparatus comprising means for supplying the trackway with code impulse combinations, means for varying the number of impulses in a combination in accordance with traffic conditions, a plurality of contacts on the train, means for selectively operating said contacts in accordance with the number of impulses in a combination being supplied to the trackway, and a plurality of governing means one controlled by each of said contacts.
37. Railway traffic controlling apparatus comprising means for supplying the trackway with code impulse combinations, means for varying the number of impulses in a combination in accordance with traffic conditions, a plurality of contacts on the train, means for selectively operating said contacts in accordance with the number of impulses in a combination being supplied to the trackway, a plurality of relays one controlled by each said contacts, and governing means controlled by said relays.
38. In an automatic train control system of the continuous inductive coded type; the combination with trackway apparatus for impressing code cycles on the track rails in which the code cycles may have different numbers of impulses in a cycle or have the same number of impulses differently time spaced, and car-carried apparatus distinctively responsive to said code cycles.
39. In an automatic train control system of the continuous inductive coded type; the combination with trackway apparatus for impressing code cycles on the track rails in which the code cycles may have different numbers of impulses in a cycle, the same number of impulses in a cycle differently spaced or cycles in which both the number of impulses and their spacing is different than that of other cycles; and car-carried apparatus distinctively responsive to said code impulse cycles.
40. In an automatic train control system of the continuous inductive coded type; the combination with trackway apparatus for impressing code cycles on the track rails in which the code cycles may have different numbers of impulses in a cycle and differently time spaced than the impulses of other code cycles, and car-carried apparatus distinctively responsive to said code impulse cycles.
41. In an automatic train control system of the continuous inductive coded type; the combination with trackway apparatus for impressing code cycles on the track rails in which the code cycles may have different numbers of impulses in a cycle and car-carried apparatus responsive to said code cycles requiring an initiating impulse to be transmitted from the trackway to render it effective and requiring the transmission of an executing impulse from the trackway to cause it to interpret the code cycle transmitted between this initiating and executing impulse.
